UNITED STATES PATENT OFFICE.

WILLIAM A. V. PORTER, OF NEW YORK, N. Y., ASSIGNOR TO DAVID WEIL'S SONS LITHOGRAPHIC COMPANY, OF BROOKLYN, NEW YORK, A CORPORATION OF NEW YORK.

COLLAPSIBLE CARTON.

1,191,583.

Specification of Letters Patent. Patented July 18, 1916.

Application filed January 21, 1916. Serial No. 73,373.

To all whom it may concern:

Be it known that I, WILLIAM A. V. PORTER, a citizen of the United States, and resident of the borough of Manhattan, in the city and State of New York, have invented a new and useful Improvement in Collapsible Cartons, of which the following is a specification.

This invention relates to an improved collapsible carton and the blank from which the same is formed, with the object in view of providing such an article which is strong and light, cheap to manufacture, and which is provided with foldable means designed to operate either as a cover for the carton, or as an easel therefor to hold the same in an inclined position for display purposes.

Another object is to provide certain improvements in the form, construction and arrangement of the parts, whereby the above-mentioned and other objects may be effectively carried out.

A practical embodiment of my invention is represented in the accompanying drawings, in which—

Figure 1 represents a plan view of the blank, Fig. 2 represents a view in perspective of the partially formed carton, Fig. 3 represents a similar view taken at a direction opposite to Fig. 2, Fig. 4 represents a top plan view of the folded and closed carton, Fig. 5 represents a section taken in the plane of the line A—A of Fig. 4, looking in the direction of the arrows, Fig. 6 represents a bottom plan view of the carton as shown in Fig. 4, Fig. 7 represents a top plan view of the carton supported by the easel and with the display panel unfolded, Fig. 8 represents a side view of the same, Fig. 9 represents a front view of the same, and Fig. 10 represents a section taken in the plane of the line B—B of Fig. 7, looking in the direction of the arrows.

The carton is designed to be formed, by a folding operation, from a suitable blank (as shown in Fig. 1), which may be stamped at one operation from appropriate sheet material, such, for instance, as cardboard. At the time of stamping or cutting out the blank, it may also be provided with the necessary creases and slits, which are utilized in folding it into box or carton formation and retaining it thus.

The blank is composed, in general, of two

main sections, which are laterally disposed with respect to each other, and are divided merely by a creasing line. One of these main sections comprises the panel 1, which is designed to form the bottom of the carton, a panel 2 designed to constitute one end of the carton, and a panel 3 which is fitted to have the combined function of a cover for the box, as well as an easel therefor, to hold the latter in an inclined position.

The other main section comprises panels 4 and 5 which are designed to constitute the sides of the carton, a panel 6 adapted to form the top of the carton, a panel 7 for forming an end of the carton, a panel 8 to act as a display surface, and panels 9, 9, and 10, 10, which are arranged to constitute reinforcing members for the ends of the carton.

In folding the blank into box form, the first step is to turn the said sections laterally upon each other into the position shown in Fig. 2, at which time the carton is in the form of an open ended rectangular tube, with the panels 4 and 5 parallel to each other and the panels 1 and 6 parallel to each other. At this juncture the flap, 11, which projects from one side of the panel 1, may be glued or otherwise secured to the inside of the panel 5. Next, the reinforcing members 9, 9, and 10, 10, are folded down upon each other so as to close the ends of the carton; after which the panels 2 and 7 are folded upon the said reinforcing members 9, 9, and 10, 10, respectively. In order to hold the end members in folded position the extremity of the panel 2 is folded at the line 12 and tucked in between the reinforcing members 9 and the adjacent portion of the top panel 6. Similarly, the extremity of the flap 7 is folded at the line 13 and tucked in between the reinforcing members 10, 10, and the bottom panel 1.

The carton is now in completely folded condition to act as a receptacle for the desired articles, and the combined cover and easel panel 3 may be used in the following manner: If it is desired to ship the goods contained in the carton, the display panel 8 is first folded flat down upon the top panel 6. Next the panel 3 is folded against the end panel 7 and then down on the top of the carton over the display panel 8. The end of the panel 3 is then tucked into the slit 15, formed in the crease 12 in the panel 2. In

this condition, the carton and its contents may be packed in any suitable manner and shipped as desired.

Upon receipt, the vendee may, for display purposes, unfold the panel 3 from the top of the carton and bend it back around underneath the same, as clearly shown in Figs. 8 and 10. When folded in this last manner the tongue 14 may be inserted in the slit 16 formed in the bottom 1. In this position, the member 3 acts as an easel, to support the carton in an angular position for displaying the contents thereof; and the panel 8 may be unfolded into an upright position, as clearly shown in Figs. 8 and 10, to expose any advertising matter which may be present on the face thereof.

When the member 3 is folded around into the easel position, it may be straightened and made more rigid by bending the strips 17, 18, at substantially right angles to the plane of the said member. This is well shown in Figs. 8 and 10.

It will be understood that various changes may be resorted to in the form, construction and arrangement of the several different parts without departing from the spirit and scope of my invention; and hence I do not intend to be limited to the particular details herein shown and described, except as they may be specifically set forth in the claims.

What I claim is:—

1. A carton having a jointed element operative as a combined cover and easel, said element having one end secured to the bottom of the carton and its other end provided with a tongue, the bottom of the carton having a slit therein fitted to receive said tongue, whereby the said element may be folded on top of the carton to act as a

cover, or be folded beneath the carton, and its tongue engaged with the slit to act as an easel for supporting the carton in an inclined position.

2. A carton having a jointed element operative as a combined cover and easel, said element having one end secured to the bottom of the carton and its other end provided with a tongue, the bottom of the carton having a slit therein fitted to receive said tongue, whereby the said element may be folded on top of the carton to act as a cover, or be folded beneath the carton and its tongue engaged with the slit to act as an easel for supporting the carton in an inclined position, and strengthening strips carried by said element and adapted to be folded out of the plane thereof to increase the rigidity of the said element when acting as an easel.

3. A carton having a jointed element operative as a combined cover and easel, said element having one end secured to the bottom of the carton and its other end provided with a tongue, the carton having a slit in its bottom and at one end of its top, said slits being adapted to receive said tongue, whereby the said element may be folded on top of the carton to act as a cover therefor and its tongue engaged with the slit at the end of the top, or be folded beneath the carton and its tongue engaged with the slit in the bottom thereof to act as an easel for supporting the carton in an inclined position.

In testimony, that I claim the foregoing as my invention, I have signed my name this 18th day of January 1916.

WILLIAM A. V. PORTER.
